UNITED STATES PATENT OFFICE.

CLEMSON L. VAN WORMER, OF MELROSE, MASSACHUSETTS.

DUMPING-CAR.

SPECIFICATION forming part of Letters Patent No. 311,047, dated January 20, 1885.

Application filed April 11, 1884. (No model.)

To all whom it may concern:

Be it known that I, CLEMSON LEROY VAN WORMER, of Melrose, in the county of Middlesex and State of Massachusetts, have invented certain new and useful Improvements 5 in Dump-Cars; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention is an improvement on that 15 class of dumping-cars in which the dumping is effected at the side by tilting the body of the car sidewise. It relates to a novel construction of the transoms, of the side bearings, 20 of the dumping devices, of the king-bolt and its adjacent parts, of the truck-post, of the device on which the side gates or swinging doors are hung, and to other features, herein-after more particularly set forth.

25 In the drawings, Figure 1 is a part of my improved car in side elevation; Fig. 2, a partial cross-section showing the transoms, side bearings, king-bolt, and rocker; Fig. 3, a partial top view of the transoms and adjacent 30 parts, the floor being removed; Fig. 4, a detail enlarged showing in perspective the end of one of the transoms; Fig. 5, the side bearings and their connections; Figs. 6, 7, and 8, side, end, and top views of a side bearing enlarged; 35 Fig. 9, a detail enlarged showing the oil-box, its worm-wheel, adjustable worm, &c., for quick dumping; Fig. 10, a top view, and Figs. 11 and 12 details, of this box; Figs. 13 and 14, enlarged views of the truck-posts; Fig. 15, 40 king-bolt detached; Figs. 16 and 17, details showing, respectively, the top of the bottom center rocker-plate and the bottom of the upper center guide-plate; Figs. 18 and 19, views of the chain-pulleys; Figs. 20, 21, and 22, details showing the gate-post boxes; Fig. 23, a detail showing a gate in its fastened and in its free position, and Fig. 24 a detail showing the conical or tapering projection on the lower rocker.

45 The upper transom, A, is constructed as fol-

lows: They are each made of two iron pieces, (marked 1,) of the form shown in Fig. 1, placed side by side, and extending across the car, and secured on the inside and under side of the outside sills, 2, and are much wider 55 than they are thick—say, for instance, six inches in width, and one inch, or thereabout, in thickness.

At the angle or bend 3 I weld a cross piece or lug, 4, which may be, say, two inches wide and 60 one and one-eighth inch in height or thickness, this lug being also of metal, and welded crosswise of both the pieces 1 and on their under side prior to bending down the part 5 of these pieces. This lug 4 thus affords a bearing when 65 the part 5 is so bent down, and makes a good fit of such part against the lug, the lug also strengthening the transom at this angle. The bottom plates or lower transoms, 6, are also in pairs side by side, and bolted, respectively, 70 to the upper transoms substantially as shown; but their extremities, instead of abutting directly against the part 5 of the upper transoms, abut against the welded cross-piece 4. The advantage of this construction is, that as there is a 75 large space, equal to nearly one-third of the breadth of the car, between the outside sills and the first or outer stringers, 7, and consequently great strain and leverage on the transom in working and dumping the car, which has a tendency to concentrate such strain at the angle 3, and would permit the ends of the lower transom if the lugs or cross-piece 4 were not there to bear and press directly on the parts 5, I entirely avoid such tendency and undue strain 80 by first strengthening the angles with the pieces 4, next fastening these pieces by welding so as to make substantially an integral part of the upper transoms, thus practically doubling the thickness and strength where 85 strength is most needed, and bringing the end-thrust of the lower transom not against the angle, but only against the pieces 4. This also lessens the lateral strain on the bolts 8.

The side bearings are shown at 9. Each 95 one is cast in a single piece and with a space between its two sides to receive two rollers, 10, 10, placed at their bottom. They are also made with an inverted-T-shaped groove, 11, running lengthwise of the tops, and which are 100

such as to adapt them for sliding in right lines on corresponding guides, 12, on the outside stringers, 7, (see Figs. 5, 6, 7, and 8,) and they also have an interior web or rib, 13, which 5 connects their two sides, so that there is sufficient strength consistent with comparative lightness. The object of these rigid sliding bearings as made with the two rollers is to give more bearing-surface than is usual with 10 side bearings, and to lessen their tendency to break down or to get out of place, and which tendency always exists more or less where the side bearing is a mere bar, or swings on a center or pivot, or has but a single point of 15 contact. The two side bearings on either side of the car are connected together by a connecting-rod, 14, and are both moved coincidentally and in the same direction by means which I shall now describe. A rod, 15, connects the side bearing at the end of the car with a lever, 16, pivoted at 17, and which may be actuated by the workman or attendant when needful. This lever has a spring, 18, which exerts a constant tendency to force the 20 lower end of the lever toward the car-frame. 25

19 is a stop which automatically locks the lever and consequently holds the side bearing to position when the lever has been moved past this stop, so that the spring can act on 30 it as above stated. It is shown as thus automatically locked in Fig. 5. A wedge-shaped key, 20, adapted to be lodged in the narrowing space, as shown, between the inclined part of the lever and the end sills or other part of 35 the car, prevents any accidental moving of the lever until this wedge has first been removed. When this wedge or key is lifted out or up, a pressure must be given to the lever crosswise of the car sufficient to overcome the force of 40 the spring 18 before the lower end of the lever can be free of the forward edge of the stop 19 and be moved backward. It will now be seen that the spring, in connection with the stop, effects an automatic locking, and that the wedge 45 prevents any proper or improper action of the lever except when desired, and that as the side bearings cannot accidentally shift their positions the car cannot dump while running nor except when positively arranged for dumping. The rod 15 has ears at its end, between 50 which the lower end of lever 17 enters, a bolt connecting these parts together.

For dumping the car I dispense with clutches on the shaft; but I employ two chain-pulleys, 55 21, fixed to the main shaft 22 at or near each end of the car. Supporting the shaft are three bearing-boxes. These chain-pulleys are keyed 21 tightly on the main shaft. Each is made with deep grooves 23, and also with shallow grooves 60 24, to receive the links of the chain and prevent its slipping.

To operate the dumping devices, I place on the main shaft near the front end of the car a worm-wheel, 26, securely fixed to the shaft, 65 and gearing with the teeth of this wheel an adjustable worm, 27, keyed or secured on a

hand-lever, 28, this lever resting on a fulcrum at its lower end in a depression on the bottom of the box 29, containing the worm-wheel. (See Fig. 9.) In the top of this box is a slot, 70 30, in which such worm-shaft or lever-arm 28 and its upper bearing, 31, are permitted a short movement or change of position for the purpose of disengaging the worm from the worm-wheel 26, this lever-arm to be thus used 75 when it is desired to dump quickly. A lever-dog, 32, serves to hold the worm either in or out of engagement with the worm-wheel 26 by causing its inner end, 33, to enter either one, as desired, of the holes 34 of the upper 80 bearing. When this dog is engaged with the hole, as shown in Fig. 9, the tilting of the car is effected slowly by the turning of the hand wheel or crank on the worm-shaft, and in this position the main shaft 22 cannot accidentally turn, but is in full control of the operator; but when it has been thus turned a little way, so that the car is ready to dump by its own gravity when released, the shifting of the worm out of engagement with its gear 85 90 permits the car to dump itself.

The king-bolt 37 and its connections and adjacent parts are as follows: It is keyed through or provided with a thread and nut at bottom end to secure the car-body to the truck. 95 Its head 38 is square for, say, six inches, more or less, to prevent its turning, and it is provided with two similar pulleys, 39, at its top, which run or bear upon the face of the top center plate. The rollers or pulleys may be 100 attached by means of a hole drilled through the top of the king-bolt and inserting a pin through this hole and fastening one of the rollers to each end of the pin and battering down each end of such pin. The under or arched 105 side of the center plate of the upper rocker, 41, is made in two parts, 42 42*, with a space, 43, between them, and each one of the pulleys or rollers 39 at the top of the king-bolt runs on one of these parts as a track, the king-bolt 110 itself passing down between them. The opening or recess 43 in the upper rocker permits the roller-head or upper end of the king-bolt when the car is tilted or dumped to ride on the parts as on a double track, or rather permits these tracks to run on the rollers in a direction opposite to that in which the car is dumped, so that the king-bolt does not move laterally, and does not need to be jointed, because its motion is only a vertical one as it is 115 lifted or lowered by the upper rocker when dumping. The upper and lower rocker cannot become separated, as the king-bolt having the rollers at the top and the nut at the bottom always holds them together. The under or arched side of the upper rocker or center plate has a curve of greater radius than that of the lower rocker, 45, and the central or higher portion of this lower rocker is made 120 flat or horizontal, to lessen or avoid a shaking motion of the car while running, which is apt to attend cars when both touch at a point only 125 130

like circles. The lower rocker or its center-plate, like the upper one, is made in two pieces, to allow the king-bolt to work freely between these pieces.

5 Instead of casting projecting pins on the face-plate of the lower rocker, as heretofore, and which are liable to be broken off, I fasten such lower center plate to the bolster by means of wrought-iron bolts having projecting or conical heads 47, adapted to fit the corresponding sockets 48 in the upper rocker. These heads, being of wrought-iron instead of being cast-iron, are much stronger than the lugs or pins which, as heretofore, have been cast as an integral part of the plate or rocker, and any blow upon them does not tend to injure or break the plate; and my bolt thus performs the double duty of a bolt and of a lug or pin to assist in keeping the rockers to their right places when dumping, and to aid the king-bolt in keeping the parts together when dumping.

Fastened to and extending upward from the lower rocker is a stout, strong projection, 48*, preferably conically shaped, (though it may be rounded off at its top,) and which extends up into the upper rocker, this projection being thus materially smaller at its top than the space left for it in the upper rocker, so that 30 while serving the duty of keeping the rockers from separating and aiding to sustain the king-bolt it yet permits all the requisite rocking motion.

The truck-posts 49 are made as follows, and are shown in Figs. 1, 13, and 14: Each one is cast whole, and with a lateral projection, boss, or swell, 50, of sufficient breadth, height, and strength to offer an oblong vertical slot or opening, 51, therein to receive and sustain a 40 chain-wheel, 52, for receiving and carrying positively and without slipping the chain 25, which tilts the car for dumping, ears 53 on the base of this column or post adapting it to be firmly secured to the truck, and holes 45 53*, transverse of such slot, serving as a journal-bearing for the axle or journal of these chain-wheels 25. The chain itself, it will be understood, is secured at its respective ends to the inside of the two outside sills of the 50 car. It will now be seen that by this construction of the truck-post it not only performs the duty of an ordinary truck-post, but it gives the firmest possible resistance to the strain of the chain in dumping or in righting 55 the car after dumping, as the whole truck receives the pull and strain in a direction cross-wise of the car, and at the points where it is best able to meet it without detriment. The truck-post and its parts which carry the chain-wheel being all integral and solid, excepting the holes cast or made therein, as above stated, it has nothing in it to shift or change position when the axis of the chain-wheel is once firmly secured therein, and when the truck-post is 60 secured to the truck; and all the pull of the chain is also in a direction transverse of the

bolts by which this post is fastened to the truck, the post affording a very rigid and unyielding guide for the chain.

My novel means for hanging the side doors 70 or gates of the car-body are as follows, and they have for their object the throwing of the doors or gates further outward by their own gravity when dumping, so as to be entirely clear of the falling load, and offer no obstruction or resistance to the full and free discharge of the load:

Cast-iron boxes 55 are secured to the uprights or posts 56, on which the gates are hung, and also to each end of the top of the 80 gates. These boxes are made as shown at Figs. 20, 21, 22, in the detail figures, and which show edge views, and plan or side views, respectively. Each box is made in a single piece or casting, and is in the form of a tube, 57, 85 with a projecting plate, 58, extending beyond such tube substantially at both its sides. At the inside edge of some of these plates, say, upon those attached to the gate, and to prevent too close proximity of the gate ends with the 90 posts, and that they may swing clear, I prefer to make a projection, 59, as shown in Fig. 22. The gate and posts being thus provided with such boxes on their outer sides, (see Figs. 1 and 23,) and the gates being then hung to place 95 by a bolt extending through the bore or tubular part of the boxes, it will be seen that the point of suspension on the bolts is materially outside of the center of gravity of the heavy gates, and that consequently even when the 100 gates are not latched or fastened they must of their own weight swing and hang so that at their bottoms they will be a foot or two outside of the car, and will require to be pushed or swung inward in order to latch them, and, 105 consequently, when the car is tilted for dumping and the latches or fastenings released, these gates will swing away far enough to let the load dump freely without any impediment, as they are not only farther away than as usually has been the case, but they are not liable to swing back to check the delivery of the load.

It will be understood that in applying these boxes to the gate posts the latter are cut away enough to receive the back half of the tubular 115 part of the boxes, so that the flat part or plate of the box may be flush with the outer face of the posts.

I claim—

1. The transoms constructed as described, 120 consisting of the two iron pieces 11, side by side, the cross pieces or lugs 4, welded thereto, and the lower transom pieces, 6, abutting at their ends against these lugs, and bolted to the pieces 1, and having their end portions 125 bent down over the lugs, all substantially as and for the purposes set forth.

2. The roller side bearings 9, constructed as described—that is, with the broad base having a cavity therein for the two bearing-rollers 10, 130 with the connecting-web 13, made integral with the sides and with the groove 11—these

bearings being applied to move in right lines only on guideways on the outside stringers, all as and for the purposes set forth,

3. The combination of devices for operating the side bearings, consisting of the rods 14 15, lever 16, and its spring and stop 19, substantially as shown and described.

4. In combination with the side bearings and with its described devices for operating it, the key 20, serving to lock the lever 16, all substantially as set forth.

5. In combination with the main shaft and with its dumping chains and pulleys, the worm-wheel 26 on said shaft, and the adjustable worm 27, arranged substantially as shown and described, and the lever-dog 32, serving to lock said worm either into or out of engagement with the worm-wheel.

6. The king-bolt 37, provided with two rollers at its upper end, and held as set forth to the truck, and applied to move in a vertical line only, in combination with guideways or tracks for such rollers made on the upper rocker, all substantially as and for the purposes set forth.

7. In combination with the dumping-chains secured at their ends to the car-frame, the truck-posts 49, each made integral or in a single piece, having the lateral boss or swell 50, the opening to receive the chain-pulley and to afford journal-bearings for the same, and having ears whereby the posts may be secured to the truck, all as shown and described.

8. In combination with the gates and their posts, the iron boxes 55, made each of a tube, 57, having a plate, 58, integral therewith projecting from the opposite sides of such tube, and applied to the outside of the gates and of their posts, as shown and described, and whereby the unlatched gates by their own gravity swing off from the car-body, and in the act of dumping swing far enough away from the car to be clear of the discharging load.

CLEMSON L. VAN WORMER.
